KEY HOLDER

Samuel F. Bashara, Houston, Tex.

Application March 16, 1931, Serial No. 523,055

2 Claims. (Cl. 150—40)

The invention relates to an improvement in keyholders in which the keys are adapted to be encased in a housing or container and to be extended therefrom when they are to be used.

5 An object of the invention is to provide a rubber key-holder which is of such construction that it may be distorted in order to extend the keys therefrom.

Another object of the invention is to provide 10 a key-holder of resilient material in which the keys are arranged to be pivoted but normally be concealed therein.

Another object of the invention is to provide 15 a rubber key-holder which will expand when subjected to pressure adjacent the ends thereof, and by this same pressure the keys will be extended from the case.

Other and further objects of the invention will 20 be readily apparent when the following description is considered in connection with the accompanying drawing, wherein:

Fig. 1 is a central vertical section taken 25 through the key-holder and showing keys positioned in the opposite ends thereof.

Fig. 2 is a side elevation looking at the key- 30 holder of Fig. 1 from the left edge thereof, and showing in dotted lines the position of the case when it is distorted to extend the keys.

Fig. 3 is a side elevation looking at the outside 35 of the key-holder.

Fig. 4 shows a slightly modified form of the 40 invention in which a partition has been provided intermediate the end of the key-holder.

Fig. 5 is an edge view of the structure shown 45 in Fig. 4.

Fig. 6 shows still another modification in which 50 all of the keys are adapted to be retained on a single pivot pin.

By having reference to Fig. 1 the key-holder 55 is shown as comprising a body 2 which may be of moulded material which is more or less resilient, and which will present a neat and pleasing appearance. It has been found that different compositions of rubber and similar materials are suitable for this case, and the description will be given in connection with a rubber case, but it is intended that other materials may be employed if desired. The body 2 is of hollow construction in order to provide a key retaining chamber 3. This chamber may be of any desired length to accommodate the size of keys to be disposed in the holder, and two smaller keys of a well known type have been shown as positioned in the opposite ends of the holder. These keys are mounted on any suitable type of pivot pin such as 4,

which is suitably mounted in the casing or body portion 2. Fig. 2 has been broken away to illustrate one form of connection for this pivot pin 4, which includes a clip or cap screw 5 which is arranged for connection to the outer end of the pin. In order to hold the pin in position in the body or casing so that it may be removed when keys are to be inserted, this cap screw 5 is attached. The keys 7 are arranged to pivot on these pins 4 by means of an opening such as 8 10 which is usually provided in the head of the key.

The body portion 2 is preferably moulded of material of the desired configuration to retain the keys and includes the two side portions 9 and 10 which are preferably identical. These side portions 9 and 10 are connected at the rear by means of the web portion 11 and are separated on the front of the holder by a slot 12. This slot 12 will appear normally as shown in full lines in Fig. 2, and the keys 7 will be enclosed within the housing as seen in Fig. 1. However, when it is desired to extend the keys for use it is merely necessary to press on the body 2 at points such as 14 and 15. This pressure when applied, will distort the housing or casing so 25 that the lips defining the slot 12 will be separated and a pressure will be exerted on the point 16 on the head of the key. This pressure will cause the key to move out through the slot 12 and the side portions 9 and 10 will be moved to the dotted 30 line portion of Fig. 2. The key can then be used and when pressure is relieved from the points 14 and 15 the casing will resume its normal position, and the key may be pushed back in through the slot 12 or the case again distorted for movement of the key.

Fig. 3 shows the outer surface 18 of the case as being smooth. It is intended, however, that suitable advertising, descriptive or ornamental configuration, may be applied on this surface. 40

Fig. 4 shows a modified form of the invention in which the web portion 11 is illustrated by the reference character 11' and is shown as having been so positioned that one-half of it is on each side of the body. In this manner the slot 12' is 45 formed in two parts, one on each side of the body so that the keys in each end will be separated. In this manner the keys at opposite ends will move from opposite sides of the housing and the web 11' crosses the body of the housing to 50 form a partition such as 19. In general respects, however, this form of the invention is the same as disclosed in the previous figures.

Fig. 5 shows how the slot 12' is provided so that it extends only part way down each side of 55

the key-holder. The key retaining pin 4 is provided in this modification the same as previously described.

Fig. 6 shows still another modification of the invention which is adapted to hold but one set of keys mounted on the single pivot 4 adjacent one end thereof. This form of the invention is identically the same as that described in connection with Fig. 1, except that it is smaller in size and the pivot pin at one end of the holder has been omitted.

Having described my invention, what I claim is:

1. A keyholder including a body of rubber or the like, said body being hollow with flat sides

and an elliptical edge configuration, a slot formed partially around each end and down opposite sides for the entrance or removal of keys, and means carried by the body to retain keys therein.

2. A keyholder including a body of rubber or the like, said body being hollow with flat sides and an elliptical edge configuration, a slot formed partially around each end and down opposite sides for the entrance or removal of keys, means carried by the body to retain keys therein, and a transverse partition dividing the body into two sections.

SAMUEL F. BASHARA.
